Primary Examiner — Janice Hallmark

(57) **CLAIM**

The ornamental design for a mobile phone cover, as shown and described.

DESCRIPTION

FIG. 1 is a first perspective view of a mobile phone cover showing my design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the mobile phone cover in which the design is embodied that form no part of the claimed design.

1 Claim, 8 Drawing Sheets
